US00D803958S

(12) **United States Design Patent** (10) **Patent No.:** **US D803,958 S**
(45) **Date of Patent:** **** Nov. 28, 2017**

(54) **ABDOMINAL EXERCISE MAT**

(71) Applicant: **Coulter Ventures, LLC**, Columbus, OH (US)
(72) Inventor: **Bonnie Elizabeth Clark**, Canton, GA (US)
(73) Assignee: **Coulter Ventures, LLC**, Columbus, OH (US)

(**) Term: **15 Years**

(21) Appl. No.: **29/577,616**

(22) Filed: **Sep. 14, 2016**

(51) LOC (10) Cl. **21-02**

(52) U.S. Cl.

USPC **D21/687**

(57) **CLAIM**

The ornamental design for an abdominal exercise mat, as shown and described.

DESCRIPTION

FIG. 1 of the drawings is a top perspective view of the abdominal exercise mat showing, in particular, the ornamental design thereof;

FIG. 2 of the drawings is a bottom view thereof;

FIG. 3 of the drawings is a front elevational view thereof;

FIG. 4 of the drawings is a back elevational view thereof;

FIG. 5 of the drawings is a first side elevational view thereof;

FIG. 6 of the drawings is a second side elevational view thereof;

FIG. 7 of the drawings is a top plan view thereof; and,

FIG. 8 of the drawings is a bottom plan view thereof.

1 Claim, 6 Drawing Sheets
